UNITED STATES PATENT OFFICE.

DANIEL CROWLEY, OF BOSTON, MASSACHUSETTS.

CONVERTIBLE TABLE, LOUNGE, AND DESK.

SPECIFICATION forming part of Letters Patent No. 350,414, dated October 5, 1886.

Application filed November 6, 1885. Serial No. 181,957. (No model.)

To all whom it may concern:

Be it known that I, DANIEL CROWLEY, a citizen of the United States, residing at Boston, in the county of Suffolk and State of Massachusetts, have invented certain new and useful Improvements in a Convertible Table, Lounge, and Desk, of which the following is a specification.

The object of my invention is to produce a convertible lounge, table, and desk; and the invention consists in a frame mounted upon adjustable standards in such manner that when used as a lounge it can be adjusted to a suitable height for sitting upon, and when desired for use as a table can be raised to the required height and the lounge turned over so that its under side will form the top of the table and the back one of the leaves; and the invention further consists in certain details of construction, hereinafter fully described, and pointed out in the claims.

Referring to the accompanying drawings, Figure 1 is a perspective view of my invention shown as a lounge, one of the end pieces being removed. Fig. 2 is a similar view shown as a table. Fig. 3 is a vertical transverse section as a table with the leaves extended. Fig. 4 is a vertical transverse section when adjusted as a desk. Fig. 5 is a vertical transverse section at one end when used as a lounge.

A A represent two side frames or standards, secured together by rods or bars B B. At the back or inner side of each of these frames is secured a socket, C, in which a rack, D, is free to work up and down. Each of these racks gear with a pinion, E, placed on a stud on the inside of the frame A, the pinions E being in gear with other pinions mounted on a rod or shaft, G, that has its bearings in the frames A. One end of the shaft G passes out beyond the frame, and is formed with a square, g, onto which a key or lever, H, fits, by which the rod G is turned so as to raise or lower the racks D through the pinions E F. If desired, the pinions E may be dispensed with and the pinions F be made to gear directly with the racks D.

I is a spring-pawl fulcrumed on the bar G, so that when in its normal position it will be in contact with the teeth of the rack D; but when desired to lower the rack the pawl may be drawn out of contact with the rack by pressing on its rear end. The upper ends of the

racks D are formed with arms or projections d, one of which is provided with a spring-latch, a, and the other with a thumb-screw, b; or they 55 may both be fitted with spring-latches or thumb-screws, and these latches or thumb-screws may be employed at one or both ends of the combined lounge and table.

J is a rectangular frame, provided at each end with a plate, j. This frame is hung by means of bolts c to the upper ends of the racks D, so that it is free to turn over, but is held in the desired position by means of the spring-latch a or thumb-screws b passing into holes 65 formed in the plate j. There is a series of these holes on each side of the plate, so as to give any desired inclination to the frame J when used as a desk, or when used as a lounge to incline the seat, if desired; but when the 70 latch or thumb-screws are in the center holes the frame will be held level.

The frame J is provided with a solid bottom, K, which, when turned over, forms the top of the table, the upper side of the frame being 75 upholstered to form the seat Q of the lounge.

The inner side of each end piece of the frame J is provided with a metal strap or socket, L, (see Fig. 5.) for the purpose of securing the head-pieces M to the frame J, each head-piece 8c M being provided with a tongue or flat piece of metal, N, which can be slipped into the socket L, so as to firmly hold the head-piece in position, and when the head-pieces are not required they can be easily removed and placed 85 in drawers P P in the frame J.

The back of the lounge consists of a flat board, R, hinged to the rear of the frame J, and upholstered on one side to form the lounge-back V, the other side serving as one of the 90 leaves for the table. When used as a lounge, the back is supported by means of hooks e, secured to the end pieces of the frame J, and passing into eyes f, secured to the back R. The back may be hung so as to be removed altogether, if desired.

S is a flat board hinged to the front of the frame J, and forms the other leaf of the table. When used as a lounge, this leaf is folded under the bottom of the frame J and secured by 100 a hook, h, passing over a pin in the side of the leaf.

T T are bolts or supporting-bars that slide in suitable recesses in the frame J, and they

are employed for supporting the leaves R S when used as a table. On one side there are two of these bolts, one, T, for supporting the leaf R, as shown in Fig. 3, and a sliding support, T', that is partially beveled off, as shown, for supporting the said leaf on a level when the table is used as a desk, as shown in Fig. 4.

If desired, brackets or supports U may be formed on the frames A, as shown in Fig. 5, so that when used as a lounge the bottom of frame J may rest upon them, thereby giving additional support thereto.

To change the lounge, as shown in Fig. 1, to a table, as shown in Fig. 2, the key or lever H is placed upon the square end g of rod G and turned, which through gears F E causes the racks D to be raised, and with them the frame J, the spring-pawl I retaining them in the raised position. When raised to the required height, the thumb screw b is loosened and one end of an ordinary spring-latch, a, withdrawn, when the frame is free to revolve on the bolts c. It is then turned half-way round, thus bringing the bottom K of the frame 25 to the top, when the table will appear as shown in Fig. 2. The hooks f, h are then drawn back and the leaves can be opened. To change the table to a lounge the operation is reversed.

When desired to form a desk, as shown in Fig. 4, the thumb-screw b and spring-latch a are inserted into the holes in plate j, so as to give the desired inclination.

Instead of the racks D and pinions, screws and worms may be employed to raise and lower the frame J, and, instead of the leaf S being hinged as shown in Fig. 1, it may be hinged as shown at s in Fig. 2, so that it is free to swing round so as to hang down, as shown in dotted lines.

Although I have described my invention with reference to a lounge, it is obvious that it would apply equally well to an easy chair, the only difference being in the length of the rectangular frame J.

I am aware of the construction shown in the patent of Wolf, No. 13,371. I am also aware that a rack has been used to raise a frame holding an invalid from a bed, as shown in English Patent 2,275 of 1872. Such I do not claim; but

What I claim as my invention is—

1. In a convertible table and lounge, the frame J, constituting the center of the seat and capable of being turned upside down, the leaves R and S, forming a portion of the table-top, the racks D, and standards A, as shown and described. 55

2. In a convertible table and lounge, the reversible frame J, in combination with the perforated plates j, a spring-latch, a, and 60 thumb-screw b at the upper end of the rack D, as and for the purpose set forth.

3. In a convertible lounge and table, the leaf R, upholstered on one side to form the back V of the lounge, in combination with the frame 65 J, upholstered on one side to form the seat Q, and the leaf S, folded underneath the frame J, as and for the purpose set forth.

4. In a convertible table and lounge, the leaf S, forming one of the leaves of the table, 70 in combination with and hinged to the frame J, so as to enable it to be folded underneath the said frame when used as a lounge, as set forth.

5. In a convertible table, lounge, and desk, 75 the combination, with the table-top K and leaf R, of a beveled sliding support, T, when the article is used as a desk, as shown and described.

6. A convertible lounge, table, and desk 80 consisting of the reversible frame J, hung to the upper ends of racks D, and upholstered on one side, and having a solid bottom, K, on the opposite side to form a part of the top of a table, the back R, forming one of the leaves 85 S of the table, the leaf S, also forming one of the leaves of the table and capable of being folded under the frame J when not in use, the rack D, and socketed standards A, connected together by bars B, gear-wheels E F, and rod 90 G, all as and for the purpose set forth.

In testimony whereof I have signed my name to this specification in the presence of two subscribing witnesses.

DANIEL CROWLEY.
